ELECTRICAL TRANSFORMER

Roger B. Kerr, Marblehead, Mass., assignor to General
Electric Company, a corporation of New York

Application December 22, 1955, Serial No. 39,427

Term of patent 14 years

(Cl. D26—15)

Fig. 1

Fig. 2

Figure 1 is a perspective view showing the front and one end of an electrical transformer embodying my new design.

Figure 2 is a side elevation thereof taken from the rear of Figure 1, the broken lines being omitted for convenience of illustration.

The dominant features of my design reside in the portions shown in full lines.

I claim:

The ornamental design for an electrical transformer, as shown and described.
